UNITED STATES PATENT OFFICE

2,472,548

AUTOMATIC TENSIONING DEVICE
FOR REELSSteve Schnell, Kirkwood, Mo., assignor to Wagner
Electric Corporation, St. Louis, Mo., a corpora-
tion of Delaware

Application February 24, 1945, Serial No. 579,539

4 Claims. (Cl. 242—75)

1

This invention relates to tensioning devices employed in connection with reels and in its more specific aspects is directed to a device for maintaining a constant tension in a web or strand of material withdrawn from a reel that employs well-known automotive devices.

One of the objects of this invention is to produce a tensioning device for a web or strand or other flexible material drawn from a reel in which the principal components of the device are well-known automotive types of brake equipment.

A further object of the invention is to provide a tensioning device in which an automotive brake secured to a reel shaft is controlled by a valve mechanism connected to a pivoted idler roller whose position is a function of the web or strand tension.

Another object of the invention is to provide a tensioning device for a web or other flexible material withdrawn from a reel in which the movements of the idler roller controlling the pressure admitted to the brake is prevented from having wide fluctuations of movement therein in order to keep the tension in the withdrawn web material constant.

Still another object of the invention is to provide a master cylinder control in a tensioning device in which the movement of the idler roller about which the web or strand is passed is responsive to the tension in the web or strand material, thereby controlling the operation of the master cylinder governing the hydraulic brake operatively connected with the reel shaft.

A still further object of the invention is to provide a hydraulic brake control for a reel of flexible material in which snubber or shock absorber devices associated with the idler roller are responsive to the tension in the flexible material to cause slower and more uniformly steady changes in the control valve governing the brake.

Other and further objects of the invention will occur to those skilled in the art to which this application pertains as the description proceeds which, taken in connection with the accompanying drawings sets forth a preferred embodiment of the invention but such disclosure is not to be construed as a limitation of the invention which is limited only by the appended claims, and any and all modifications, alterations and

2

variations of structure coming within the spirit and scope thereof are deemed to be included herein.

In the drawings:

5 Figure 1 is a schematic view of the essential elements of the tensioning device;

Figure 2 shows in detail the construction of the idler roller support; and

Figure 3 shows an end elevational view of the idler support with the snubber devices attached.

The necessity of keeping web or strand tension substantially constant in devices such as printing presses, strip paper, wire and cloth printing mills, et cetera, is recognized in the several arts as well as in others cognate thereto. A constant tension is found necessary in the paper mill and printing press arts et cetera because the correctness of the impression and the relationship of the position of the roller with respect to the web material passing the same must be constant in order to maintain the correctness of the impressions in the several roll passes through which the web material is delivered. Various devices have been developed in the arts for controlling tension, all of which are rather involved and complicated in design. It is the purpose of the instant invention to produce a tensioning means for a reel which employs well-known mechanism commonly used in the automotive and related arts that are applied to the reel in a new and novel way in order to produce a result superior to that in the prior art.

The objects and advantages sought above are achieved in the device disclosed in the accompanying drawings in which the numeral 1 illustrates a reel shaft on which a reel or supply of web or other flexible strand 2 is wound and which is preferably of paper or other fibrous material. A suitable frame is customarily provided 30 on which this reel may be mounted in order to support the same for rotation. Operatively associated with the reel is a brake mechanism comprising a pair of automotive type brake shoes 3—3 pivoted to a suitable backing plate (not shown). Securable to the backing plate is a 35 brake cylinder or pressure fluid-operated motor 4 whose function is to expand the shoes into engagement with the brake drum 30 mounted on the reel shaft 1. Each of these devices, as indicated above, is conventional in the art and its

operation is believed clearly understood. The flexible material 5 is passed around an idler roller 6 rotatably mounted in pivoted frame elements 7 and 8 between which a member 6a is held in parallel relation to roller 6. The frame elements 7 and 8 are secured to a shaft 9 journaled in appropriate supports 10 and 11 that may be secured to the frame of the press or other device receiving the web material. After passing about roller 6, the web material is led around the second idler roller 12 before entering the press or other mechanism receiving the flexible material 5. The shaft 9 has a lever or arm 13 rigidly secured thereto rotatable with the shaft. An adjusting screw 14 is rotatably disposed in an ear or other nut element 15 secured to an appropriate base having a spring 16 operatively associated therewith and the other end of spring 16 is connected to the free end of lever 13. This mechanism including the adjusting screw 14 and spring 16, acts to initially tension the flexible material 5 to the proper degree.

The brake cylinder 4 is operated by a master cylinder or compensator 17 driven by a compressed air motor 18 rigidly connected to the compensator 17. A more detailed construction of these members is shown in United States Patent No. 2,361,419 (see parts 13 and 14). A conduit 19 is connected to the exhaust side of compensator 17 leading to brake cylinder 4 in a well-known manner. The conduit 19 has a fitting 20 therein which is connected to brake cylinders or brake operating motors 21 and 22 provided with protective boots 21' and 22', respectively, and acting as shock absorbers or snubbers for arm 13. One end of each of these motors is pivoted to arm 13 by means of appropriate pivot pins and the other ends of the motors are appropriately secured to fixed parts of the machine with which the reel is associated. A conduit 23 is connected to fitting 20 and leads to the brake cylinders or motors 21 and 22. A detailed disclosure of the construction of these cylinders is shown in United States Patent No. 2,254,887 which shows a similar motor device. Regulating valves 24 and 25 are connected in the conduits leading to the respective motors 21 and 22 in order to control the ingress and egress of pressure fluid thereto.

The air motor 18 has a conduit 26 connected thereto having a shut-off valve 27 inserted therein. The conduit 26 is connected to a metering type control valve 28, shown in detail in United States Patent No. 2,259,809, which has a conduit 29 connected thereto leading from an appropriate source of compressed air. The movable element of valve 28 is mechanically connected to arm 7 of the roller mechanism by means of linkage 28a operatively connected to member 6a on the idler mechanism 6. Therefore, valve 28 determines or measures the flow of compressed air to motor 18. The power output of the air motor 18 operating compensator or master cylinder 17 determines the pressure admitted to brake cylinder 4.

The operation of the above device is dependent upon the position of idler mechanism 6, 7, and 8 with respect to valve 28. Since valve 28, as previously indicated, measures the amount of pressure fluid to be applied to the brake cylinder 4, it follows that said valve 28 is responsive to the tension in flexible material 5. The positioning of frame element 7 of the idler mechanism is, therefore, a direct function of the ten-

4
sion in flexible material 5, consequently controlling the brake shoes 3-3 and brake motor 4 as previously indicated.

The operation of the above described device is dependent upon the position of idler roller 6 and its supporting arms relative to valve 28. The spring 16 seeks to rotate the idler assembly counter-clockwise about shaft 9 and since frame elements 7 and 8 are mechanically linked to the actuator on valve 28, any counter-clockwise movement will allow more air to pass to motor 18. Counter-clockwise motion is only possible when too much slack is present in web 5. The increased quantity of air admitted to motor 18 by valve 28 will cause the brake motor 4 to urge shoes 3, 3 into engagement with drum 30 to slow down reel 2. If reel 2 travels too slowly, web 5 will rotate the idler assembly in a clockwise direction about shaft 9 against spring 16, thereby reducing the flow of compressed air to motor 18 and reducing the pressure of shoes 3, 3 and drum 30, thereby allowing reel 2 to increase its rate of speed and enabling web 5 to be unwound at a greater rate. The positioning of idler roller 6 and arms 7, 8 is, therefore, a direct function of the tension in web 5 which thereby controls the brake assembly 3, 4, and 30.

Wide swings of movement in idler roller 6 and arms 7, 8 are prevented by pressure fluid devices 21 and 22 functioning as shock absorbers or snubbers. As will be noted, these have one end pivoted to opposite sides of lever 13 and the other ends of the devices are suitably pivotally anchored to the machine frame on which the device is mounted. Each of devices 21 and 22 is connected to conduit 19 and valves 24 and 25 are connected in the conduit ahead of the devices and devices 21 and 22 are, therefore, connected to the compensator 17. The devices 21 and 22 act against or oppose each other. The fluid flows freely from one to the other when the idler roller 6 is raised or lowered. The valves are adjusted to regulate this flow and thereby control the rate of swing of roller 6 and its frame elements 7, 8. The rate of flow is also a function of the tension in web 5, the pressure in conduit 19, and the tension in spring 16, in addition to the setting of valves 24 and 25. When valves 24 and 25 are properly adjusted, movement of pressure fluid from one to the other will be regulated to slow up the swinging motion of roller 6. The motion of roller 6 and arm 13 is thereby stabilized, enabling the material 5 to be withdrawn from reel 2 at a more uniform rate.

Having fully described my invention, that which I claim as novel and desire to protect by Letters Patent of the United States is:

1. In an unreeling device; a reel for web material; a brake for said reel; a pressure fluid motor for actuating said brake; a compensator for supplying pressure fluid for actuating said pressure fluid motor; means for actuating said compensator; a source of power for said means; an idler mechanism for said reel which includes a pivoted frame having a roller therein about which said web material passes; a spring connected to said idler mechanism for tensioning said web material; a pair of shock absorbers operatively associated with said idler mechanism for preventing excessive movements in said idler mechanism; means operated by said idler mechanism for controlling said source of power for said means; and means for establishing com-

munication between said compensator, said shock absorbers and said pressure fluid motor.

2. In an unreeling device, a reel for web material; a brake for said reel; a pressure fluid motor for actuating said brake; a compensator for supplying pressure fluid for actuating said pressure fluid motor; a second pressure fluid motor for actuating said compensator; a source of pressure fluid for operating said second pressure fluid motor; an idler mechanism for said reel which includes a pivoted frame having a roller therein about which said web material passes; means connected to said idler mechanism for tensioning said web material; a pair of shock absorbers operatively associated with said idler mechanism for preventing excessive movements in said idler mechanism; means operated by said idler mechanism for controlling said source of pressure fluid for said second pressure fluid motor; and means for establishing communication between said compensator, said shock absorbers and said pressure fluid motor.

3. In an unreeling device, a reel for web material; a brake for said reel; a hydraulic motor for operating said brake; a compensator for supplying pressure fluid for said hydraulic motor; a pressure fluid operated motor for actuating said compensator; a source of pressure fluid for said last mentioned motor; an idler mechanism for said reel which includes a pivoted frame having a roller therein about which said web material passes as it is unwound from said reel; a spring connected to said idler mechanism for tensioning said web material; shock absorber means connected to said idler mechanism for preventing wide swings of movement in said idler mechanism; a valve for said source of pressure fluid; means connecting said valve and said idler mechanism to thereby vary the output of said last mentioned pressure fluid motor; and

means for establishing communication between said compensator, said shock absorber means and said hydraulic motor.

4. In an unreeling device; a reel for web material; a brake for said reel; a hydraulic motor for operating said brake; a compensator for supplying pressure fluid for said hydraulic motor; a pressure fluid operated motor for actuating said compensator; a source of pressure fluid for said last mentioned motor; an idler mechanism for said reel which includes a pivoted frame having a roller therein about which said web material passes as it is unwound from said reel; means connected to said idler mechanism for tensioning said web material; a shock absorber disposed on each side of said idler mechanism for preventing wide swings of movement in said frame; a valve for said source of pressure fluid; means connecting said valve and said pivoted frame to thereby vary the output of said last mentioned pressure fluid motor; and means for establishing communication between said compensator, each absorber and said hydraulic motor for enabling said shock absorbers to be responsive to pressure fluid produced by said compensator.
